(57) **CLAIM**

The ornamental design for a connected electrostimulator, as shown and described.

DESCRIPTION

Reproduction **1.1** is a bottom view of a connected electrostimulator showing my new design.

Reproduction **1.2** is a perspective view thereof with one electrode of the connected electrostimulator detached.

Reproduction **1.3** is an enlarged perspective of a portion of the connected electrostimulator with a part thereof detached.

Reproduction **1.4** is a side view of the connected electrostimulator.

Reproduction **1.5** is a front view thereof.

Reproduction **1.6** is a perspective view thereof.
